UNITED STATES PATENT OFFICE.

CHARLES VALENTA, OF CHICAGO, ILLINOIS.

CARPET-STITCHING DEVICE.

1,339,307.

Specification of Letters Patent.

Patented May 4, 1920.

Application filed February 21, 1919. Serial No. 278,503.

To all whom it may concern:

Be it known that I, CHARLES VALENTA, a citizen of the United States, residing at Chicago, in the county of Cook and State of

5 Illinois, have invented certain new and useful Improvements in Carpet-Stitching Devices, of which the following is a specification.

My invention relates to stitching machines 10 and particularly to a unitary portable machine for stitching seams of carpets and the like which have been ripped or if desired, for fastening together the adjacent pieces of carpet in the first instance.

15 My invention relates to a single acting device of such compactness and arrangement as can be used to repair ripped seams of carpets without removing the carpet from the floor, the stitching being done by forming 20 staples and pressing the same through the edges of the carpet.

One of the objects of my invention is to provide a simple and efficient portable carpet stitching machine.

25 Another object is to provide a unitary portable stitching machine which may be operated by hand for inserting staples and the like to fasten together adjacent edges of carpet.

30 A further object is to provide a carpet stitching machine having staple forming means and staple driving means as well as means for holding the edges of the carpet for forming either a butt joint or lap joint.

35 These and other objects of my invention will be apparent from an observation of the drawings, wherein—

Figure 1 is a side elevational view of the preferred embodiment of my invention.

40 Fig. 2 is an elevational view looking at the machine from the left hand end of Fig. 1.

Fig. 3 is a vertical sectional view on line 3—3 of Fig. 1.

45 Fig. 4 is a top plan view of Fig. 1, and

Fig. 5 is a vertical sectional view, somewhat enlarged, showing certain features of the invention in detail.

The preferred embodiment of my invention 50 which I shall herein describe includes a bottom plate 10, a front plate 11, a side plate 12 and a back plate 13. The back plate 13 is preferably reinforced by a brace member 14 as seen in Figs. 1 and 5. In the bottom 55 plate 10, there is formed an aperture 15 through which the operating elements of

my device pass. Underlying the aperture 15 is an anvil for securing the pieces of carpet to be fastened together in operative position with respect to the fastening means to 60 be hereinafter more fully described. This anvil I have chosen to form of metal and arranged in such a manner as to provide two spaces for the reception of the pieces of carpet. In Fig. 2, the anvil is shown in end 65 section and includes a member fastened at 16 to the plate 10 having an offset portion 17 spaced from the plate 10 but parallel thereto and another portion 18 bent back on itself to form a space similarly situated with respect to the one between the member 17 and the bottom plate 10. In Fig. 1 this anvil is shown as it appears from the right end in Fig. 2, the purpose being to receive the carpets in overlapping relation to form 75 preferably a lap joint. If, however, it is desired to form a butt joint, the same anvil may be used but the pieces of carpet applied thereto in a slightly different manner, which will be more fully described herein- 80 after.

In the form shown I mount rearwardly of the front and back plates 11 and 13, a reel or spool 19 supported on arms 20 and which reel is adapted to carry a coil of wire 85 21 from which the staples are formed as required. The wire 21 is led from the reel or spool through an opening in the feeder bar 22 and through an opening 23 in one of the vertical supports 24. To feed the wire 90 forwardly as required and in the manner hereinafter described I provide the feeder bar 22 with an enlarged opening 25 and pivot therein a plate 26, the lower end of which is provided with teeth 27 for gripping 95 the wire 21 as the bar is rocked about its support 28. The plate 26 is so mounted as to grip the wire 21 in only the forward movement of the bar and to free the wire as the bar is rocked backwardly or toward the spool 19. To retain the wire in position while the feeder bar is being rocked backwardly to grip the wire to move the same forwardly, I provide a toothed dog 29 adapted to coöperate with a ledge 30 and which 105 dog 29 is held by means of a spring 31 in engagement with the wire 21. The dog 29 and the coöperating spring 31 act to prevent the wire from being withdrawn while permitting forward movement thereof by 110 the feeder bar 22.

Mounted between the front and back

plates 11 and 13 and the side plate 12 are two relatively reciprocal plungers 32 and 33 both of which are arranged to pass through the opening 15 in the bottom plate 10. The plunger 32 is provided at its lower end with bifurcated portions 34 and 35 to form fingers, which portions are spaced to provide a slot therebetween. The plunger 33 has an end portion overlying the fingers 34 and 35 and is adapted to slide thereagainst. The plunger 32 on its rear side is provided with pins 36 and 37 between which the short arm 38 of the feeder bar 22 is received and by which the feeder bar is actuated as the plunger 32 is reciprocated. To maintain the plungers 32 and 33 in upward or normal position as shown in Fig. 3, I provide springs 39 and 40 resting against abutments 41 and 42 secured to the back and front plates and at their other ends engaging shoulders 43 and 44 in the plungers 32 and 33, respectively. Pivoted at 46 between the front and back walls 11 and 13 is an arm 45 curved as shown in Fig. 5 and having an outwardly extending shelf or foot 47 which when the arm is in the position shown in Fig. 5 underlies the ends of the fingers 34 and 35 of the plunger 32. The rear of the plunger 32 has formed therewith a lug 48 which is adapted to bear against the curved portion of the arm 45 under certain conditions as the plunger 32 is reciprocated to move the foot 47 from beneath the end of said plunger. The lug 48 and the curve of the arm 45 are so associated that the foot 47 is retained underneath said plunger for a certain portion of the travel of the plunger which will be more fully explained hereinafter. The wire 21 is adapted to be fed by the feeder bar and the associated parts forwardly through the aperture 23 in the support 24 and over the foot 47 of the arm 45. The parts are so arranged that the wire is fed forwardly until the front end rests against the plate 12 and there is brought to rest, the position of the various parts being shown clearly in Fig. 3. Thereupon, to form a staple from the wire 21, the plunger 32 is moved downwardly by means herein-after explained bringing the fingers 34 and 35 onto the wire, the finger 35 acting in conjunction with the face of the vertical support 24 to shear off the wire. Continued movement downwardly of the plunger 32 bends the ends of the wires so sheared over the foot 47 into an inverted U-shaped staple 49. In the meantime, the plunger 33 has started downwardly and as downward movement of the two plungers is continued, the lug 48 acts to withdraw the foot 47 supporting the wire which is now a staple 49 from support thereof and the plunger 33 has been moved to engage the staple 49 and is ready 60 to drive the same through the pieces of

carpet or similar material A and B which have been previously inserted in the anvil in the manner described and as shown in section in Fig. 3. Continued downward movement of the plunger 33 drives the staple 49 through the overlapped edges of the pieces of carpet and by engagement of the downwardly projecting ends of the said staple with the portions 18 of the anvil the ends are turned inwardly and the staple 75 clenched in position in the usual manner of clenching a staple. The pressure for moving the plungers 32 and 33 downwardly now being relieved the springs 39 and 40 become effective to return them to the normal or inoperative position.

As a means for reciprocating the plungers 32 and 33, relatively to each other, I prefer to employ a handle 50 pivoted near its outer end at 51 to a suitable support 52 of the frame and which handle has formed thereon two cam surfaces 53 and 54, cam 53 engaging plunger 32 and cam 54 engaging plunger 33. As means to retain the handle 50 in normal or inoperative position, as shown 90 in Fig. 1, I employ a spring 55 secured to the handle 50 as shown and at the other end to a portion of the framework of the machine.

It is believed that the operation of my 95 invention has now been clearly pointed out and that one skilled in the art could readily employ the same to fasten together pieces of carpet.

I shall, however, explain the operation of 100 my invention so that the same may be clear. Referring to Fig. 3, pieces of carpet A and B are inserted in the anvil with the edges overlapped. The machine may be brought to receive the edges of a ripped seam of carpet while the carpet is still on the floor in which instance, the anvil would be moved underneath the edges of the carpet in the same manner as if the pieces of carpet were brought together in the position shown in 110 Fig. 3. When in this position the handle 50 is moved downwardly by the operator, which downward movement reciprocates first the plunger bar 32 to form the staple. Continued movement of the handle then reciprocates the plunger 33 which is the driving or presser bar to drive the staple through the carpet, the foot 47 having been withdrawn from underneath the staple in the meantime. When the handle has been depressed so that the staple has been formed and clenched in the carpet, the operator removes his hand therefrom and the springs 39, 40 and 55 act to return the plungers and handle to normal or inoperative position, 125 as shown in the drawings.

By my invention I have provided a simple, efficient and readily portable carpet stitching machine of such a form as to be utilized in repairing ripped seams without 130

removing the carpet from the floor, or if desirable, the machine may be utilized to fasten together strips of carpet to make a floor covering. I have also shown the machine as being arranged to be actuated manually. I do not wish to be considered as confining the scope of my invention to such manual operation as I am aware that it would be possible to apply power means to 10 such a device to accomplish the same result without materially changing any of the operative features.

While I have described more or less precisely the details of construction, I do not 15 wish to be understood as limiting myself thereto, as I contemplate changes in form and the proportion of parts and the substitution of equivalents as circumstances may suggest or render expedient without departing 20 from the spirit or scope of my invention.

I claim:

1. A machine of the character described comprising in combination a pair of vertically 25 movable plungers mounted for relative reciprocation side by side, means for feeding wire laterally in the path of movement of said plungers, the lower end of one of said plungers being shaped to constitute 30 a shearing means for the wire and the lower end of the other of said plungers being shaped to set a staple formed from said wire, and a manually operable handle mounted to swing above and across the 35 upper ends of said plungers and having its lower edge formed to provide cams of differing contours, said cams acting respectively upon the upper ends of said plungers to impart a longitudinal thrust thereto by 40 wiping across the upper end thereof.

2. A device of the character described comprising a base plate having an aperture formed therethrough, an anvil disposed below said aperture, upstanding back and 45 front plates carried by the base plate, a pair of vertically disposed plungers mounted to slide between the back and front plates, a lever pivoted between said back and front plates, connections between the lever and one 50 of said plungers for imparting swinging movement to said lever, a feeding dog carried by said lever adapted to engage a wire to be fed, a holding means mounted between the back and front plates for engaging a 55 wire to be fed to prevent reverse movement of the same, means for forcing said plungers downwardly at predetermined times, spaced

fingers upon the lower end of one of said plungers, a support coöperating with one of said fingers to constitute a shear for the wire, 60 a lever pivotally supported from an extension of the back plate having a curved face that is disposed toward said plungers and a supporting foot adapted to swing in beneath said plungers and beneath said wire and a 65 projection upon one of said plungers for engaging said lever to force the supporting foot from beneath the wire after said plunger has moved downwardly a predetermined distance. 70

3. A device of the character described comprising a base plate, spaced back and front plates, vertical guide ways between the back and front plates, a pair of vertically movable plungers between the back 75 and front plates comprising over-hanging shoulders in their lengths, fixed abutments between the back and front plates, springs bearing between said abutments and the shoulders of the plungers, a lever pivoted between the back and front plates for swinging movement, means for imparting swinging movement to said lever from one of the plungers, a wire feeding means carried by said lever for feeding wire transversely across the path of movement of the plungers, a pair of fingers at the lower end of one of said plungers, a fixed support between the back and front plates with which one of the fingers coact to constitute a 80 shearing means for the wire, the lower end of the other of said plungers acting between said fingers, a lever pivoted to swing in a vertical plane and carrying a foot which moves from a point in the rear of said 85 plungers to a point beneath said plungers, said lever having a curved face and a projection upon one of said plungers coacting with said face to thrust the said lever rearwardly upon downward movement of the 90 plunger, a manually operable handle mounted to swing above and across the upper ends of said plungers and having its lower edge formed to provide cams of different contours, said cams acting respectively 95 upon the upper ends of said plungers to impart a direct longitudinal thrust thereto against the tension of said spring by wiping across the upper ends of said plungers. 100

Signed at Chicago, Illinois, this 14th day of February, 1919.

CHARLES VALENTA.
